UNITED STATES PATENT OFFICE.

FRANK M. COLLORD, JOSEPH C. ROHE, AND LEVIN D. GASS, OF DANVILLE, ILLINOIS.

RAILROAD-SIGNAL.

No. 863,784.

Specification of Letters Patent.

Patented Aug. 20, 1907.

Application filed December 31, 1906. Serial No. 350,151.

To all whom it may concern:

Be it known that we, FRANK M. COLLORD, JOSEPH C. ROHE, and LEVIN D. GASS, citizens of the United States, residing at Danville, in the county of Vermilion 5 and State of Illinois, have invented certain new and useful Improvements in Railroad-Signals, of which the following is a specification.

Our invention relates to improvements in railroad signals. Its objects are principally to provide for giving 10 an audible danger signal, also a cautionary signal, as in approaching an open-switch, also a station, a crossing or other point along the railroad, also for calling attention to, or indicating that fact inaudibly as by designating the same upon suitable means operated 15 synchronously with giving the audible signal and from means actuated by such audible signal; also to provide for setting the signal-actuating means in event of the inadvertent partial opening by an engine, for instance, of the switch; also to insure with certainty the setting 20 signal-actuating means; and to provide for carrying out these objects in a simple, expeditious and effective manner.

Said invention consists of certain features or instrumentalities substantially as hereinafter fully disclosed 25 and particularly pointed out by the claims.

In the accompanying drawing illustrating the preferred embodiment of our invention—Figure 1 is a side elevation of the invention giving a general view thereof, partly in section. Fig. 2 is an enlarged detailed side 30 view of the inaudible indicator, together with the air-pressure valve actuating means and certain adjunctive parts, also the danger signal or open-switch actuating shoe. Fig. 3 is a like broken view of the inaudible indicator with the means for directly actuating the 35 same. Fig. 4 is a broken perspective view of the same together with the open-switch, derail, or danger signal annunciator. Fig. 5 is a broken plan view disclosing more especially the open-switch, derail, or danger-signal actuating shoe or trip and its switch-connection, 40 a station-indicator actuating shoe or trip. Fig. 6 is a broken detailed view, partially in section and partially in elevation, of the switch-rail connection for the danger, derail or open-switch signal operating shoe or trip. Fig. 7 is an enlarged plan view in detail of the 45 trip-connection between the switch-rail and the danger or open-switch actuating shoe or trip, and Fig. 8 is a side view, and Fig. 9 is a vertical longitudinal section of the same. Fig. 10 is a perspective of a portable shoe or trip for "flagging" purposes. Fig. 11 is a detailed 50 plan of the latter. Fig. 12 is an enlarged detailed side elevation, partly in section, showing more fully the depressing spring for the shoe-actuated wheel which controls one of the signal-operating pistons. Fig. 13 is a partly side view, and partly sectional view of the 55 shoe or trip for actuating the danger signal. Fig. 14 is a broken plan view, showing more especially the

pressure supply pipe connection between the piston-cylinders of the danger-signal and indicator actuating means. Fig. 15 is a detailed side view of one of the cylinder pistons. Fig. 16 is a vertical section of the 60 inaudible indicator.

In the disclosure of our invention, we suitably locate and secure in position upon a car, operated by a motive fluid, electricity or otherwise, at the forward or controller end thereof, or in an engine-cab, the various 65 parts as disclosed by the upper portion of Fig. 1; the parts in the extreme lower portion thereof being suitably secured in position at an eligible point upon the car or engine truck, within a suitable distance from the surface, and wherein 1 and 2 are two cylinders preferably 70 yoked together as at 3 or otherwise, this being merely a detail incident to the assembling of said cylinders for the uses of our invention. Within each of these cylinders is arranged a piston 4 whose diameter, however, is less than that of the inner cross-section of 75 the cylinder, although suitably applied to the piston, above it are packing rings 5, of course, as indicated, filling the cylinder in transverse section. The less diametered piston provides for a certain amount of surrounding space for the reception of air pressure or 80 other pressure fluid as in delivering force or pressure upon the piston in returning it to its depressed or original position after having been elevated as presently more fully disclosed.

A roll or wheel 6 is hung or suspended below each 85 cylinder from a preferably broad flat spring 7 having one end suitably secured and adapted to be coiled around a stud or pin 89 of the cylinder supporting casting and having a horizontal portion suitably supported in position for supporting each wheel or roll 6 and 90 adapted to return said roll or wheel to its normal or original position after having been elevated by the shoe or trip 8, two trips or shoes 8, 88 being suitably arranged alongside of the track one for each roll or wheel, which will be further described later on. 95

An indicator 9 suitably equipped with a tape or ribbon 10 having indicia thereon, such as railroad stations, crossings, water-tanks, block-signals, or any other information it may be desired to impart to the motorman or engineer, is suitably supported in position conveniently to the latter. The tape or ribbon 10 is coiled or wound in opposite directions upon two rolls 11 suitably journaled in the indicator casing or housing. One of said rolls is hollow and has arranged therein a spring suitably adapted to deliver its tension upon said roll as 100 the tape or ribbon is unwound therefrom in order to provide for the reverse action of the roll when the ribbon has been unwound from the same, and is to be rewound thereon. The recoil action of said spring effects the rewinding of the tape at the stated intervals 105 by the action of the signal-actuating mechanism when the car has reached its destination and is performing its 110

return trip, the detaining mechanism next described employed in connection therewith having been previously accordingly readjusted. Said detaining mechanism comprises a perforated disk 12 fixed to the indicator-casing and a detent 13 spring-cushioned or seated in a suitable housing 15 secured to the indicator-casing. Said detent has its outer or ineffective end provided with a suitable knob or finger-piece for its convenient manipulation by hand, it being automatically held in engagement with said disk at its toothed end by a spring B arranged in said housing 15 adapted to deliver its pressure upon said pawl.

A link or arm 16, suitably pivoted for convenience upon a projecting portion 17 of the shaft of one of the tape-carrying rolls, carries the detent or pawl 13 for effecting the engagement of the latter with the disk 12, said link or arm being connected to a rod 18 equipped with a suitably packed piston 19 arranged in a cylinder or casing 20. Said piston is subjected to the tension of a spring 21 coiled around said rod 18 and also inclosed within the casing 20, for effecting the release of the detent after the link, with the detent, has made its forward movement. To the lower end of the cylinder or casing 20 is connected a pipe 21 connecting with the cylinder 1, from which it receives air-pressure or like force for delivery to said casing or cylinder 20 for actuating, through said piston and adjunctive parts, said detent, as when the trip 8 actuates the signal-operating wheel 6. The air-pressure at this juncture passes into the cylinder 1 via the air supply pipe 22 leading to the air supply reservoir (not shown) for delivery to the piston 4 and thence into pipe 21. A whistle 23, suitably applied to the pipe 21 serves as an audible signal when the aforesaid action of parts takes place, as will be readily appreciated. A second pipe 24 connecting with the cylinder 2 in like manner equipped as the cylinder 1 as relates to a piston, &c., also connects with a cylinder 25 provided in like manner as cylinder 20 with a piston carrying, by means preferably of an angular arm 26, an annunciator 27, being preferably a metal-plate having noted thereon any word or symbol suggestive of extreme precaution or danger, the cylinder 2 being arranged in connection with the open switch, derail, or "flagging" shoe or trip 8. Also connected with the pipe 24 is a whistle or audible signal 28 which serves as an additional warning to the motorman or engineer of approach to an open-switch or other danger-point. A piston-equipped cylinder 29 is also applied to the pipe 24, whose piston A is subjected to the tension of a spring 30, the purpose of which will be apparent later. Also a pipe 31 leading to the high pressure air reservoir (not shown) is equipped with a valve 32, having its handle 33 connected by a rod or link 34 with the spring-cushioned piston A arranged in the cylinder 29 for the retention of the air-cut off valve 32 initially or normally closed. Said pipe 31 has a valve-equipped arm or branch 34 leading to the brake-cylinder for applying the brakes simultaneously with the applying of the danger signal. A still further pipe 35 having connection with the pipe 31 and cylinder 1 and provided with a manually-actuated valve 36 provides for delivering air-pressure by suitably operating said valve, to the upper end of the cylinder, said pipe also having a branch pipe connection 37 with the cylinder 65 2 for a like purpose in connection with the latter.

The shoe 8 before referred to, suitably pivoted in position, rests at its free end upon an arm 38 pivoted to and between the members of a stud 39 fixed to a base-plate 40 suitably secured to the rail-ties. To said pivoted arm is connected by a link 41 the upward curved or bent end of a piston rod 42, whose piston 43 is spring-seated within a cylinder 44 suitably secured in place upon the plate 40. Said piston 43 is adapted to exert pressure upon a series or number of preferably steel balls 45 upon which is superposed, within a pipe-extension 46 of the cylinder 44, an upright piston 47 arranged immediately under, and adapted to engage the lower surface of the shoe or trip 8, said pipe-extension 46 being suitably held in place by a brace 49. The spring acting upon the piston 43 is normally under tension so that it will deliver pressure upon the latter when the switch is thrown to open-position, as will more fully appear later on.

To the switch-rail point 50 is suitably connected, preferably by a nut-equipped hooked bolt 51 passing through a slot 52 of the adjacent main-track rail 53 and hooking into an aperture 54 in one end of a slide or bar 55 for effecting the switch-rail point. The slide or bar 55 has pivoted to it near its other end, a spring-pressed latch or dog 56 overhanging a forward extension 57 of said slide or bar and upon which its beak-end rests. Said beak or free end of said slide 55 engages a slot or aperture 58 of a T-shaped bar or cross-head 59 having its arms entering, and guided within slots 60 in the lower edges of parallel upright plates 61 of a box-like casting 62 suitably secured in place.

A disk or pulley 63, suitably journaled in position, is provided with a fixed lever-arm 64 and to said arm is connected, by a chain or cable 65 said slide or bar 59, said arm or lever having suitable connection, as by a wire or cable 66 or otherwise, with the bent-upward portion of the piston-rod 42 of the piston 44.

A cam or trip 67 is slidably supported in position in a vertical slot 68 in one of the plates 61 and has double recurved faces or surfaces for engagement with a lateral stud 69 of the latch 56 arranged for contact with the latter, said cam being held against one of the plates 61 by a nut-equipped stud 70 thereof extending through the slot 68.

It will be noted that, should the switch be left or thrown open, as by an oppositely moving engine or otherwise, the hook or latch 56 will, with the movement of the intermediate parts connected to the switch, be deflected or lifted over and past the cam 67, and thus provide for the disengagement or release of said latch 115 from the bar or cross-head 59. Instantly the spring-piston 44 will be thrust, by the action of its spring, forward, throwing the upright piston 47 upwardly into contact with, and elevating or setting the shoe or trip 8. Of course the intermediate balls 45, forming practically 120 a flexible joint will readily conform to the aforesaid action of parts, rolling upward along the elbow-like portion of the pipe-extension 46. Also, it will be noted that, with the forward movement of the piston-rod 42, the jointed or link connection 41 will also be carried 125 forward and accordingly allow the pivoted arm 38 to conform to the movement of, and still retain its alignment with, and support the free end of the shoe or trip 8.

It will be further observed that, in the reverse move- 130

- ment of the parts as takes place in closing the switch, the latch 56, being in depressed position, will lift, and readily pass under the freely slidable cam 69, after which the latter will automatically drop to its former position, again allowing the piston 44 to be put under the stress or tension of its spring for like action of the parts as first described.
- It is further noted that, in event of an engine passing from the main track to the siding and deflecting or spreading the points of the switch-rails, which would have the effect to partially open or actuate the switch, the latch or dog 56 would, even by the relatively slight movement thus transmitted to the parts, become disengaged from the cross-head or slide 59, by the direct resistance thus opposed to said dog or latch by the cam 67, thus allowing the spring of the piston 43, to deliver its tension or pressure to elevate the piston 47 and set the shoe or trip 8 for actuating the signal upon an approaching engine, as aforesaid.
- 20 The shoe or trip 88 is stationary or not actuated as the shoe or trip 8, only being principally used for actuating a station or like indicator signal, although also adapted for sending in an audible or whistle signal as above made apparent.
- 25 A portable trip or shoe 71, suitably adapted for being placed at any required point along the railroad-track, as for "flagging" a train, is provided with spring-pressed or adjustable jaw or cleat-like-equipped bars 72, 73 effective for clamping, or application to a rail o 30 the railroad-track, as clearly disclosed by Fig. 10.
- We claim—
1. A device of the character described, comprising a piston, with its cylinder provided with air-pressure supply means, means for initially actuating said piston, an audible signal and an indicator, means effective for simultaneously delivering air-pressure from said cylinder to said audible signal and said indicator, valve-equipped means for delivering air-pressure into said cylinder for effecting the return stroke of its piston, for cutting off the air-pressure supply in arresting the sounding of the signal.
  2. A device of the character described, comprising a piston, with its cylinder provided with air-pressure supply means, means for initially actuating said piston, an audible signal and an indicator, means effective for simultaneously delivering air-pressure from said cylinder to said audible signal and said indicator, valve-equipped means for delivering air-pressure for effecting the return-stroke of said piston, and means for automatically controlling the opening of the valve of said valve equipped means.
  3. A device of the character described, comprising a piston, with its cylinder provided with air-pressure supply means, means for initially actuating said piston, an audible signal and an indicator, means effective for automatically delivering air-pressure from said cylinder to said audible signal and said indicator, valve-equipped means for delivering air-pressure for effecting the return-stroke of said piston, means for automatically delivering air-pressure to, and for opening the valve of the aforesaid valve equipped means, said means for opening said valve being itself automatically controlled and arranged in connection with the air-pressure delivery means for said signal and indicator.
  4. A device of the character described, comprising a number of pistons, one of their cylinders having direct connection with air-pressure supply means and the other cylinder connected to the aforesaid cylinder for its air-pressure supply, means for initially actuating either of said pistons, a number of audible signals and indicators, means effective for automatically delivering air-pressure from said piston-cylinders to said audible signals and indicators, valve-equipped means for delivering air-pressure for effecting the return-stroke of either of said pistons for arresting the sounding of the signal.
  5. A device of the character described, comprising a number of pistons, one of their cylinders having direct connection with air-pressure supply means and the other cylinder connected with the aforesaid cylinder for its air-pressure supply, means for initially actuating either of said pistons, a number of audible signals and indicators, means effective for automatically delivering air-pressure to audible signals and indicators, valve-equipped means for delivering air-pressure for effecting the return-stroke of either of said pistons for arresting the sounding of the signal, and means for automatically controlling the opening of the valve of said valve-equipped means from the air-pressure delivery means to said signals and indicators.
  6. A device of the character described, comprising a piston, air-pressure supplying means for the cylinder of said piston, a danger signal embracing a piston carrying an annunciator, air-pressure means delivering from said cylinder into the cylinder of the latter, means for producing an audible signal connecting with said air-pressure delivering means, a roll or wheel equipped to lift the first-referred to piston and having arranged in connection therewith a coiled spring by the recoil-action of which said wheel or roll is automatically returned to its initial position.
  7. A device of the character described, comprising a piston with its cylinder provided with air-pressure supply means, an audible signal, means for delivering air-pressure from said cylinder to said audible signal, valve-equipped means receiving air-pressure, for delivery into the upper end of said cylinder and additional valve-equipped means for automatically controlling the first-noted valve-equipped means, means for operating said piston and means for actuating said piston operating means.
  8. A device of the character described, comprising a piston with its cylinder provided with air-pressure supplying means, a signal having air-pressure supply connection with said cylinder, means for operating said piston, a pivoted shoe or trip having connection with a switch, and means for elevating said shoe or trip when the switch is in open position.
  9. A device of the character described, comprising means operated by air or like pressure, means for operating a signal from said air-pressure operated means, a pivoted shoe or trip for actuating said air-pressure operated means and means effecting connection between said shoe or trip and a switch embracing a sliding cross-head, a pivoted latch or dog engaged with said cross-head and a cam effective to trip or disengage said latch or dog from said cross-head in opening the switch.
  10. A device of the character described, comprising an air-pressure operated piston, a signalling contrivance, means for delivering air pressure from the cylinder of said piston to signalling contrivance, means for lifting said piston into elevated position, means for lifting said piston-actuating means, embracing a pivoted shoe and means of connection between said shoe and a switch, including means adapted to release a spring-pressed piston engaging said shoe in opening the switch.
  11. A device of the character described, comprising a piston with its cylinder provided with air-pressure supply means, means for initially actuating said piston, said piston being of different diameters one commensurate with that of the interior of its cylinder, and the other of less diameter, a signalling contrivance actuated from an automatically depressible piston, and an air-pressure conducting pipe connecting said piston-cylinders for the delivery of air-pressure to the automatically depressible piston for displaying the signal, and air-pressure delivery means connecting with the cylinder containing the piston of different diameters.
  12. A railway signal comprising a number of pistons, with their cylinders, air-pressure supply means for said cylinders, a signal-displaying contrivance and an indicator both operated from automatically depressible pistons, means for initially actuating the first referred to pistons, air-pressure delivery pipes leading from the cylinders of said first referred pistons and delivering into the cylinder containing said automatically depressible pistons and valve-equipped air-pressure delivery means for effecting the return-stroke of each of said first-referred to pistons.

4
tons, and means for controlling the action of the valve of said valve-equipped means.

13. A device of the character described, comprising a signaling contrivance carried upon a car or engine and switch-actuated mechanism, including a pivoted shoe or trip arranged alongside of the track, a piston effective for engagement with said shoe, a cylinder or tube containing a number of spheres or balls assembled in said tube or cylinder and supporting said piston in projected position, and means also arranged in said tube or cylinder for the delivery of the opening action of said switch-actuated mechanism upon said balls or spheres.

14. A device of the character described, comprising a signaling contrivance carried upon a car or engine and switch-actuated mechanism, including a pivoted shoe or trip arranged alongside of the track, a piston effective for

engagement with said shoe, a cylinder or tube containing a series of balls or spheres assembled in said tube and supporting said piston in projected position, a second piston engaging the opposite end of said ball-series and having applied to its rod a spring delivering its stress or tension upon the latter piston, and an upstanding lever connected to the otherwise free end of said trip or shoe, and connecting means between said rod and said lever.

20 In testimony whereof we affix our signatures, in presence of two witnesses.
